[57] CLAIM

The ornamental design for a flush door latch assembly,
as shown and described.

DESCRIPTION

FIG. 1 is a left side, front and top perspective view of
our design for a flush door latch assembly;

FIG. 2 is a plan view thereof;

FIG. 3 is a front elevation view thereof;

FIG. 4 is a left side elevation view thereof;

FIG. 5 is a right side elevation view thereof; and,

FIG. 6 is a bottom view thereof.

The rear view of the flush door latch assembly is unornamented.

The broken line showing in FIGS. 1, 2, and 4-6 is for
illustrative purposes only.
